T. A. Witherspoon
Attorney.

UNITED STATES PATENT OFFICE.

GEORGE W. BEADLE, OF NEW YORK, N. Y.

POSITIVE-STRIP FOR MOVING-PICTURE MACHINES.

1,245,424.

Specification of Letters Patent.

Patented Nov. 6, 1917.

Application filed September 21, 1915. Serial No. 51,879.

To all whom it may concern:

Be it known that I, GEORGE W. BEADLE, a citizen of the United States, residing at New York city, in the county of New York and State of New York, have invented certain new and useful Improvements in Positive-Strips for Moving-Picture Machines; and I do hereby declare the following to be a full, clear, and exact description of the invention, such as will enable others skilled in the art to which it appertains to make and use the same.

This invention relates to moving picture films or strips made of paper, and has for its object to provide a strip adapted to carry the positive pictures of moving picture machines, which strip will be less expensive to manufacture and more durable in use than are the celluloid films or strips now employed.

With these and other objects in view the invention consists in the novel details of construction and combinations of parts, more fully hereinafter disclosed and particularly pointed out in the claims.

Referring to the accompanying drawings forming a part of this specification, in which like numerals designate like parts in all the views—

Figure 1 is a plan view of a portion of a positive strip made in accordance with this invention; and

Fig. 2 is a sectional view of the parts shown in Fig. 1.

The strip 3 of transparent paper or of other transparent material, is provided at its edges with the perforations 20, and along said edges are secured in any suitable manner, the reinforcing member 16 provided with perforations 17 adapted to register with the said perforations 20. In cutting said perforations 17, however, they are shaped as shown, so as to provide the oblong ears 18 on each side of the perforations 17, and the smaller ears 19, at each end of said perforations 17.

After these said perforations 17 are thus formed the ears 18 are folded over or through the perforations 17 and glued or

otherwise secured to the other side of the 50 paper strip 3, as will be clear from the drawings. The ears 19 are likewise folded through and secured to the underside of the strip 3 as will also be clear from Fig. 2. The finished perforation is disclosed at 20 in 55 Fig. 1 and the driving pins of the moving picture machine will contact with the bent over edges 21 of the ears 18, and thus prolong the life of the strip 3.

It will thus be seen that I make a positive 60 moving picture film or strip out of paper, I reinforce the edges of the strip and also I reinforce the edges of the perforations in the said strip to the end that the life of the strip is greatly prolonged.

It is obvious that the body portion 3 being made of paper instead of celluloid, it will in all cases be non-explosive.

What I claim is:—

1. A moving picture film comprising a 70 body portion of transparent material having perforations along its edges; a reinforcing member provided with perforations registering with said first named perforations secured to one side of said transparent 75 strip; and reinforcing ears integral with the edges of said second named perforations passing through said first named perforations and secured to the other side of said transparent strip, substantially as described. 80

2. A moving picture film comprising a body portion of transparent paper material having perforations along its edges; a continuous paper reinforcing member provided with perforations registering with said first 85 named perforations secured to one side of said transparent strip; and reinforcing ears integral with the side and end edges of said second named perforations passing through said first named perforations and secured to 90 the other side of said transparent strip, substantially as described.

In testimony whereof I affix my signature, in presence of a witness.

GEORGE W. BEADLE.

Witness:

SAUL W. LEVY.
